United States Patent Office

Des. 193,100
Patented June 26, 1962

193,100

WHEELED TOY VEHICLE

Marcel O. De Vos, Grosse Pointe Woods, Mich., assignor to National Production Co., Detroit, Mich., a corporation of Michigan

Filed Dec. 27, 1961, Ser. No. 68,093

Term of patent 14 years

(Cl. D34—15)

I claim:

The ornamental design for a wheeled toy vehicle, substantially as shown.
